UNITED STATES PATENT OFFICE.

OTTO S. MURPHY, OF PEORIA, ILLINOIS.

HASP-LOCK.

1,111,028.

Specification of Letters Patent. Patented Sept. 22, 1914.

Application filed August 1, 1913. Serial No. 782,454.

To all whom it may concern:

Be it known that I, OTTO S. MURPHY, citizen of the United States, residing at Peoria, in the county of Peoria and State of Illinois, have invented certain new and useful Improvements in Hasp-Locks, of which the following is a specification.

My invention relates to improvements in hasp locks, the principal object being to provide a lock of that character which cannot be picked or tampered with to effect an opening, and which locks itself automatically.

To the accomplishment of the foregoing and such other objects as may hereinafter appear, my invention consists in the construction, combination and arrangement of parts hereinafter described and then sought to be defined in the appended claims, reference being had to the accompanying drawings forming a part hereof and which illustrate a preferred embodiment of my invention; it being understood however that various changes may be made in practice within the scope of the claims without digressing from my inventive idea.

In the drawings:—Figure 1 represents a perspective view of a device constructed according to my invention in use as a latch; Fig. 2 is a plan view of the locking portion of the device in a locking position, the cover being removed; Fig. 3 is a similar view showing the device in an unlocked position; Fig. 4 is a perspective view of one of the tumblers; Fig. 5 is a front view of the bolt; Fig. 6 is a rear view of the bolt, and, Fig. 7 is a plan view of the compartment or chamber formed in the hasp for receiving the various operating parts of the lock.

Referring now to the drawings the numeral 1 designates the shank or hasp which is secured to staple 2 and has a body portion 3 having the slotted or apertured lug or ear 4 extending therefrom and adapted to be hooked or secured on the lug or hook 5, as indicated in Fig. 1, so that the device may be used as a latch. The lug or hook 5 is the means with which the lock itself engages.

The body portion 3 of the hasp is in the form of a rectangular chamber or compartment 6, having the cover 7, which is provided with the aperture 8 and a slot 9 to receive the barrel or key cylinder 10, the lower end of which is reduced and rotatably mounted in the aperture 11. This body por-

tion is provided near its front end with the elongated slot or opening 12, which is adapted to receive the locking lug or hook 5. The guiding and guarding flange or abutment 13 is provided adjacent the aperture 12 and extends from the lower side of the body to a position in line with the middle part of said opening or aperture 12. The pins, lugs or extensions 14 and 15 are provided in an intermediate portion of said chamber or compartment and form means for guiding the movement of the bolt into and out of engagement with the locking lug or hook. Extending inward from the opposite side edge of the chamber or compartment is the guiding arm or member 16 which is spaced from the bottom as shown, and beneath which is provided the extended guiding lug or rib 17. In the lower corner of said chamber or compartment is provided the extended pin 18. As stated hereinbefore, the various operating means are adapted to be positioned in said chamber or compartment and include the bolt 19 and the tumblers, and the key barrel or cylinder 10. The bolt 19 is formed in two parts as illustrated, the body portion 20 and the toe or locking portion 21 which has secured thereon the pin or stud shaft 22 by means of which said toe or locking member is pivotally secured to said body portion or member 20.

The body portion or member 20 is of peculiar and irregular shape, having its front face flat with the exception of the extending supporting flange 23, the lower face 24 of which is beveled or rounded, as shown, this supporting flange terminating short of the rear edge of the body member. The lower portion of the body member is provided with a depending lug or extension 25, the inner side of which merges into a recess 26, one side wall 27 of said recess being beveled and the other side 28 being curved and merging into the straight bottom edge 29 of said bottom member. The bottom portion of said body member 20 terminates on the extended lug 30, the front edge of said body portion or member 20 extending upwardly therefrom in the form of the curve 31, the initial portion of said side or edge being straight as at 32, to provide the bearing or abutment portion. The upper edge of said front portion is below the top edge of the main part of the body portion to provide room for the spring 33, which is secured to

said body portion 20, and the end of which bears on the toe or extension 21. The rear side of said body member or portion 20 is provided in its main portion with the extended groove or recess 34, in which is adapted to be positioned the guiding rib or lug 17 so as to hold the bolt in its proper position while moving from its locked to its unlocked position. The forward portion is 10 reduced as at 35, to provide room to receive the toe or extension 21, part of which is reduced as at 36 so that the combined thickness of the reduced portion of the body member and toe member of the bolt are substantially equal to the thickness of the body member of the bolt. By reducing the portion of the toe or extension the shoulder or abutment is provided which is positioned in engagement with the front edge 32 of the 15 body portion. The underside of the toe or extension is cut away to provide the recessed portion 37, the forward extremity of the toe 38 being in line with the bottom straight edge 29 of the body member. The forward portion of the bottom side of said toe or extension 21 is beveled as at 39, and the front thereof is inclined, as at 40 to receive the end of the spring 33 when said toe or extension is moved on its pivot by the engagement of the beveled surface 41 of the locking lug or bolt. The straight bottom edge 29 normally rests on and is guided by the pin, lug or extension 14 and the flange or abutment 13. The pin, lug or extension 35 is positioned immediately above the flat upper edge 42 of said toe or extension 21 and engages the top portion of the shoulder or abutment 35, which is provided by reducing the front portion of said body member 30 so as to prevent said locking member being projected too far by means of the spring 43 which is secured to the extended pin 18 and bears against the rear edge of the body member 20, as shown. The guiding 40 arm or member 16 is positioned so as to engage the flat front face of the body member 20 of the bolt so as to hold it in its proper position during its movement.

The bolt proper is held normally in its 50 locked position by means of the spring 43, as has been described, and which is prevented from being moved to an unlocked position by means of tumblers 44. These tumblers are of a peculiar shape and are pivotally mounted on the extended pin or shaft 22, the aperture 45 being provided for that purpose. Each tumbler is provided with the two rear extensions 46 and 47, spaced apart as shown, to provide a recess or opening 48, which in the unlocked position as 55 shown in Fig. 3 is entered by the guiding arm or member 16. The upper extension 46 of each tumbler is longer than the lower extension 47, and has the cut out portion 49 providing the bearing toe 50 and the lock-

ing abutment or shoulder 51, it being understood that in a locked position as shown in Fig. 2, the locking shoulder or abutment is in engagement with the arm or member 16. The lower edge of each tumbler is rounded or concaved as at 52. The spring 53 is secured to the lower portion of each tumbler and curved to the front end thereof with its extremity 54 engaging on the beveled or curved flange 23, as shown in Figs. 2 and 75 3, whereby each tumbler is normally held in position to prevent the retraction of the bolt, that is when the locking shoulder or abutment 51 is in engagement with the end of the arm or member 16. It is therefore 80 obvious that the bolt cannot be retracted until the tumblers are released from engagement with the arm or member 16 to permit the entrance of said arm or member 16 into the slot or opening 48 in the tumblers as 85 they move rearwardly.

The key 55 is the opening means having the lugs and recesses thereon formed to operate the tumblers and the bolt. The key first engages the convexed under surface 90 52 of the tumblers, lifting them and moving them on their pivots 22 until the locking shoulder or abutment 51 is free from the end of arm or member 16. At this time the operating lug on the key engages the rear wall 95 27 of the recess 26 and upon further rotation of the key, moves the bolt together with its attached tumblers to the rear against the spring 43 until the toe 21 of the bolt is withdrawn from the opening or aperture 100 12 and from the hooked lug 5, so that the hasp is released. When the key is released the lug and its attached tumblers return to their normal position due to the action of spring 43, and the key may then be withdrawn. By having the toe constructed separate from the body portion of the bolt, the lock may be engaged with the hook or lug 5 merely by positioning the same in the opening and using sufficient force to cause 110 said toe 21 to turn it on its pivot 22 against the tension of said spring 33 until the toe is lifted high enough to permit the passage of said lug 5, when said toe 21 will be forced into the hook by means of spring 33 and the 115 hasp will be locked.

What I claim is:—

1. A lock of the character described, including a shank portion and a body portion, said body portion having an opening in the 120 bottom thereof, a bolt slidably mounted in said body portion and normally held across said opening, tumblers pivotally mounted on said bolt having portions normally in engagement with a stop or abutment, said tumblers being adapted to be actuated by a key to be withdrawn from engagement with said abutment whereby the bolt may be withdrawn from its position across said opening.

2. A lock of the character described, in- 125 130

cluding a shank portion and a body portion, said body portion having an opening in the bottom thereof, a bolt slidably mounted in said body portion and normally held across said opening, tumblers pivotally mounted on said bolt having portions normally in engagement with a stop or abutment, and having a recess or opening therein, said tumblers being adapted to be actuated by a key to be withdrawn from engagement with said abutment whereby the bolt may be withdrawn from its position across said opening, said stop or abutment being adapted to enter said recess or opening in said tumblers.

15 3. A lock of the character described, including a shank portion and a body portion, said body portion having an opening in the bottom thereof, a bolt slidably mounted in said body portion and normally held across said opening, means for guiding said bolt in its movement between its locked and unlocked positions, tumblers pivotally mounted on said bolt having portions normally in engagement with a stop or abutment, said tumblers being adapted to be actuated by a key to be withdrawn from engagement with said abutment whereby the bolt may be withdrawn from its position across said opening.

4. A lock of the character described, including a shank portion and a body portion, said body portion having an opening in the bottom thereof, a bolt slidably mounted in said body portion and normally held across said opening, means for guiding said bolt in its movement between its locked and unlocked positions, said means including spaced pins, lugs or extensions on said body portion engaging said bolt and an extended lug or rib, said bolt having a recess or groove into which said extended lug or rib fits and slides, tumblers pivotally mounted on said bolt having portions normally in engagement with a stop or abutment, said tumblers being adapted to be actuated by a key to be withdrawn from engagement with said abutment whereby the bolt may be withdrawn from its position across said opening.

5. A lock of the character described, including a shank portion and a body portion, said body portion having an opening in the bottom thereof, a bolt slidably mounted in said body portion and normally held across said opening, said bolt having a toe or extension pivotally mounted thereon and normally held in position across said opening but being adapted to move on its pivot to permit the entrance of a locking lug or hook through said opening, tumblers pivotally mounted on said bolt having portions normally in engagement with a stop or abutment, said tumblers being adapted to be actuated by a key to be withdrawn from engagement with said abutment whereby the bolt may be withdrawn from its position across said opening.

6. A lock of the character described, including a shank portion and a body portion, said body portion having an opening in the bottom thereof, a bolt slidably mounted in said body portion and normally held across said opening, said bolt being formed in two parts, a body portion and a toe or extension, said toe or extension being pivotally connected to said body portion and having means limiting its downward movement relative thereto with a spring for normally holding it in its lowermost position, said body portion having means adapted to be engaged by a key and means for normally holding said bolt in its locked position, tumblers pivotally mounted on said bolt having portions normally in engagement with a stop or abutment, said tumblers being adapted to be actuated by a key to be withdrawn from engagement with said abutment whereby the bolt may be withdrawn from its position across said opening.

7. In a lock of the character described, a member having an opening through the bottom thereof adapted to permit the entrance of a locking lug or hook, a bolt mounted in said member and normally held in its position across said opening to engage said locking lug or hook, said bolt including a body portion and a toe or extension, said toe or extension being pivoted to said body portion and adapted to be moved relative thereto to permit the entrance of said locking lug or hook, resilient means for normally holding said toe or extension in engagement with said locking lug or hook, the body portion of said bolt being provided with a bearing flange, tumblers pivotally mounted on said bolt, a stop or abutment with which said tumblers are adapted to engage, resilient means connected to said tumblers and resting on said bearing flange for normally holding said tumblers in engagement with said stop or abutment, said tumblers being adapted to be moved from engagement with said stop or abutment by means of a key, and said bolt being adapted to be withdrawn from said opening by means of a key after the tumblers are withdrawn from engagement with said stop or abutment.

8. In a lock of the character described, a member having an opening through the bottom thereof adapted to permit the entrance of a locking lug or hook, a bolt mounted in said member and normally held in its position across said opening to engage said locking lug or hook, said bolt including a body portion and a toe or extension, said toe or extension being pivoted to said body portion and adapted to be moved relative thereto to permit the entrance of said locking lug or hook, resilient means for normally holding said toe or extension in engagement with

said locking lug or hook, the body portion of said bolt being provided with a bearing flange, tumblers pivotally mounted on said bolt, a stop or abutment with which said tumblers are adapted to engage, resilient means connected to said tumblers and resting on said bearing flange for normally holding said tumblers in engagement with said stop or abutment, said tumblers being adapted to be moved from engagement with said stop or abutment by means of a key, and said bolt being adapted to be withdrawn from said opening by means of a key after the tumblers are withdrawn from engagement with said stop or abutment, means for guiding said bolt during its movement from its locked to its unlocked positions.

9. In a lock of the character described, a member having an opening through the bottom thereof adapted to permit the entrance of a locking lug or hook, a bolt mounted in said member and normally held in its position across said opening to engage said locking lug or hook, said bolt including a body portion and a toe or extension, said toe or extension being pivoted to said body portion and adapted to be moved relative thereto to permit the entrance of said locking lug or hook, resilient means for normally holding said toe or extension in engagement with said locking lug or hook, the body portion of said bolt being provided with a bearing flange, tumblers pivotally mounted on said bolt, a stop or abutment with which said tumblers are adapted to engage, resilient means connected to said tumblers and resting on said bearing flange for normally holding said tumblers in engagement with said stop or abutment, said tumblers being adapted to be moved from engagement with said stop or abutment by means of a key, and said bolt being adapted to be withdrawn from said opening by means of a key after the tumblers are withdrawn from engagement with said stop or abutment, means for guiding said bolt during its movement from its locked to its unlocked positions, said stop or abutment being positioned above said bolt so that in moving to its unlocked position said bolt is positioned thereunder.

10. A lock of the character described including a shank portion and a body portion,

said body portion having an opening therein, a bolt slidably mounted in said body portion and normally held across said opening, 55 said bolt being formed in two parts, a body portion and a toe or extension, said toe or extension being pivotally connected to said body portion, said body portion having an extended lug with which said toe or extension is adapted to engage to limit its downward movement, a spring connected to said body portion and bearing on said toe or extension for normally holding it in its lowermost position, said body portion having 60 means adapted to be engaged by a key, and means for normally holding the said bolt in its locked position, said means being actuated to be released by the manipulation of the proper key.

11. A lock of the character described including a shank portion and a body portion, said body portion having an opening therein, a bolt slidably mounted in said body portion and normally held across said opening, 75 said bolt being formed in two parts, a body portion and a toe or extension, said toe or extension being pivotally connected to said body portion, said body portion having an extended lug with which said toe or extension is adapted to engage to limit its 80 downward movement, a spring connected to said body portion and bearing on said toe or extension for normally holding it in its lowermost position, a depending lug or extension on the lower portion of said body member adapted to be engaged by a key member, a supporting flange at the top edge of said body portion of the bolt, tumblers pivotally mounted on said bolt adapted to engage a stop or abutment, springs connected to said tumblers with their free ends resting on said supporting flange of the body portion of the bolt, said tumblers being adapted to be actuated by a key to be withdrawn 95 from engagement with said abutment whereby the bolt may be moved from its position across said opening.

In testimony whereof I affix my signature, in presence of two witnesses.

OTTO S. MURPHY.
